DELAYED AUTOMATIC GAIN CONTROL
CIRCUITRene A. Braden, Collingswood, N. J., assignor to
Radio Corporation of America, a corporation of
Delaware

Application November 19, 1936, Serial No. 111,569

7 Claims. (Cl. 250—20)

My present invention relates to automatic gain control arrangements for radio signalling systems, and more particularly to a novel and improved type of delayed automatic volume control circuit for a radio receiver.

One of the main objects of my present invention is to provide an automatic volume control arrangement for a radio receiver, wherein the volume control action is delayed until signals of a predetermined amplitude are received, the volume control circuit essentially comprising a device of uni-directional conductivity whose conductivity is directly controlled by a signal rectifier of the diode type.

Another important object of the invention may be stated to reside in the provision of a delayed automatic volume control circuit for a radio receiver, wherein the control circuit comprises a diode rectifier circuit adapted to render a second diode circuit operable and conductive upon reception of signals above a predetermined amplitude, the current flow in the second diode circuit being utilized to provide the volume control bias.

Still other objects of my invention are to improve generally the efficiency of operation of delayed automatic gain control circuits for radio receivers, and more especially to provide such control circuits in an economical and reliable construction capable of ready assembly in radio receivers of present day design.

The novel features which I believe to be characteristic of my invention are set forth in particularity in the appended claims; the invention itself, however, as to both its organization and method of operation will best be understood by reference to the following description taken in connection with the drawing in which I have indicated diagrammatically a circuit organization whereby my invention may be carried into effect.

Referring now to the accompanying drawing, there is shown in the latter a superheterodyne receiver of a well known type. The receiver embodies the usual signal collector A, such as a grounded antenna circuit; the latter impressing the collected signals upon one, or more, stages of tunable radio frequency amplification. The radio frequency amplifier is denoted by the reference numeral 1, and the tunable input circuit thereof includes the tuning condenser 2. The grounded cathode circuit of amplifier 1 may include the customary biasing network 3 which provides initial bias for the signal grid of the amplifier, and the amplified output of amplifier 1 is impressed upon the tunable input circuit 4 of

the mixer, or converter, stage. The variable tuning condenser 5 of the input circuit 4 has its rotors arranged for uni-control adjustment with the rotors of condenser 2. The dotted line 6 will be understood as designating the uni-control adjusting element of the receiver tuning mechanism. The converter stage has been conventionally represented, but the reference numeral 7 is to be understood as designating the usual first detector and local oscillator circuits which are provided in present day superheterodyne receivers.

For example, the numeral 7 may designate a tube of the 2A7 type whose circuits are arranged to enable it to function as a pentagrid converter. In such case it will be understood that the condenser rotors of the oscillator tank circuit and detector input circuit will be arranged for uni-control by the element 6. Of course, and as is well known, the network 7 may employ separate first detector and local oscillator tubes. These circuits are so well known to those skilled in the art that further description is not believed necessary. It is merely essential to point out that in the output circuit 8 of the converter network there appears signal energy of intermediate frequency; and the circuit 8 is tuned to the operating IF. The latter may be chosen from a range of frequency values of 75 to 500 k. c. Of course, higher frequency ranges may be used. The IF amplifier may comprise as many stages as desired, and the numeral 9 denotes conventionally one, or more, such stages of IF amplification. The IF-tuned input circuit 10 is reactively coupled to the output circuit 8 of the converter network, and the resonant output circuit 11, tuned to the IF, is reactively coupled to the resonant input circuit 12 of the last stage of IF amplification 13.

The circuit 12 is tuned to the IF, and the resonant output circuit 14 of amplifier 13 is similarly tuned to the operating IF. The numeral 15 denotes a signal grid biasing network disposed in the grounded cathode circuit of amplifier 13, and it will be understood that similar biasing networks are employed to provide the normal signal grid bias in each of networks 7 and 9. The tuned input circuit 16 of the second detector stage 17 is reactively coupled to the output circuit 14, and is also resonated to the operating IF. The detected signals of the network 17 which includes a signal detector of suitable type such as a diode, may be impressed upon one, or more, audio frequency amplifiers, and the amplified audio cur-

rents can be utilized in any translating device, such as a reproducer of the loudspeaker type.

In order to overcome the effects of fading, an automatic volume control arrangement (hereinafter referred to as AVC) is employed. The function of this volume control circuit is to vary the gain of each of the amplifying tubes in such a manner that the signal carrier amplitude at the input circuit 16 of the second detector is maintained substantially uniform over a wide range of signal carrier amplitude variation at the signal collector A. Early AVC systems were affected by the modulation of the carrier which resulted in compression of the volume range of the received signal. This is avoided by using a diode instead of a triode, or pentode, rectifier to generate the AVC bias. Systems which get audio voltage and AVC voltage from the same diode have several faults. Generally, the AVC voltage is not large enough, or does not increase rapidly enough with increase in signal at the diode. This can be partially corrected by driving the diode harder and introducing delay. Delay in this circuit results in amplitude distortion, and it is difficult to get enough delay to make the AVC characteristic really flat. A better scheme is to use separate diodes for signal and for AVC, working at a fairly low signal level, and amplifying the AVC diode output with a direct current amplifier. Any amount of delay can then be introduced. The principal bad feature of this circuit is that it almost invariably motorboats. A minor drawback is that the SPU has to be connected to give both negative and positive voltages with respect to ground. A less troublesome procedure is to tap off signal at the second detector, and pass it through an IF amplifier followed by a diode detector. Most circuits using this arrangement attempt to apply the necessary delay to this signal-rectifying diode. This results in dependence on the modulation, if the delay is large enough to be very effective in flattening the output variation curve. My present arrangement applies the delay to a second, non-rectifying diode, and thus largely avoids effects of the modulation on the AVC voltage. Considerable help in this direction is given by the reduction in modulation which occurs in the output circuit of the rectifying diode, because of the long time constant of this circuit.

Signal energy for the automatic volume control circuit is taken off from the plate circuit of amplifier 13, and such IF energy is impressed upon the signal grid 18 of the multiple function tube 19. The signal grid 18 is connected to the tap 21 on resistor 20, resistor 20 being connected to ground through condenser 101 and at the other end being connected to the plate side of output circuit 14 through condenser 22. A substantially fixed grid bias is maintained by connecting grid 18 through the high resistance 102 to the negative end of the cathode resistor 25. The tube 19 is of the well known duo-diode-pentode type, but the two anodes of the tube are strapped together and are conventionally represented by a single anode designated by the numeral 23. As is well known, such tube comprises a pentode section and two diodes, all three having their cathodes connected together, but being otherwise independent.

The plate of the pentode section of tube 19 is connected to a desired point of positive potential through the primary winding T_1 of a coupling transformer T. The secondary winding T_2 of the coupling transformer is connected in

series between the cathode bias resistor 25 of tube 19 and the diode anode 23. In series between the cathode 24 and diode anode 23 there are arranged the resistor 25, shunted by condenser 26; the resistor 21, shunted by condenser 28; and the secondary winding T_2 . The junction of resistors 25 and 27 is adjustably connected to a desired point on potentiometer P, and it will be understood that the reference numeral 30 denotes a tap connected to the junction of resistors 25 and 27. This tap can be adjusted to a desired point on potentiometer P which has a predetermined positive potential with respect to ground.

The terminals of potentiometer, or bleeder, resistor P are connected to points of predetermined positive and negative direct current potential, the negative terminal being at ground potential. Those skilled in the art will readily understand that the bleeder resistor P may be included in the usual direct current power supply circuit of the receiver. A second diode device 40 has its cathode connected by a conductor 41 to the anode side of resistor 27. The anode of diode 40 is connected to ground through resistor 42, a condenser 43 shunting the resistor 42 to ground.

The anode side of resistor 42 is conductively connected to the signal grid circuits of the various signal transmission tubes whose gains are to be automatically controlled, by means of the conductor designated by the reference letters "AVC". The AVC or control circuit includes a filter network comprising a series resistor 50 and shunt condenser 51. An additional bias circuit for controlling the last IF tube is connected from a tap on grid circuit of tube 13. A circuit for controlling the converter tube is connected from the same tap, or a separate tap, as shown, on resistor 42, through filter 106-107, to the signal grid circuit of the converter tube included in the converter system 7. Appropriate direct current blocking condensers are disposed in the input circuits of the controlled tubes as exemplified by condenser 104.

In considering the operation of the delayed AVC circuit disclosed herein, it is first pointed out that the IF signal voltage is impressed on the signal grid 18 of the pentode section of tube 19 by means of the tapped resistor 20. Tap 21 regulates the input signal voltage impressed on the grid of tube 19, which will generally be in the range from 10% to 50% of the signal voltage developed across tuned circuit 14. The upper limit of permissible input is that at which tube 19 is on the verge of overloading when signal collector A is picking up the maximum signal which the receiver is required to receive and control. The IF energy is amplified by the pentode section of tube 19, and is impressed on the rectifier circuit 14 including diode 24-23, through transformer T. It is desired that the selectivity at the diode anode 23 be no greater than that applied to the signal detector 17. This is conveniently arranged by connecting 18 to primary circuit 14 rather than to secondary circuit 16, and by making T much less selective than circuit 16, preferably by making T_1 and T_2 so large that they are approximately tuned to the IF by the distributed capacities plus the electrode capacities of the tube elements connected to them. The resistor 27, shunted by the condenser 28, functions as the diode load, and the cathode and anode electrode of the diode are both maintained at a common positive potential with respect to ground by connection 30. The diode 75

40 has connected in circuit therewith its load resistor 42, which is shunted by the condenser 43. Since diode 40 and resistor 42 are connected across resistor 27 and to ground, the voltage E_2 , 5 tapped off from across bleeder resistor P, is in series with the diode 40 in such a sense as to bias the anode of diode 40 negatively with respect to its cathode. This results in the diode 40 being non-conductive, if the voltage developed across resistor 10 27 is less than the voltage E_2 . This follows from the fact that the direct current voltage developed across resistor 27 by the flow of rectified current therethrough, is opposite in polarity to the voltage E_2 .

15 As the voltage drop across resistor 27 increases, due to the increase in IF voltage impressed between the diode electrodes 24-23 which occurs if the signal applied to A is gradually increased from a small value, the anode of diode 40 becomes 20 less negative. Eventually it becomes positive with respect to the cathode, with the result that current begins to flow through the diode 40 and the load resistor 42. From that point on, the direct current voltage across resistor 42 increases in 25 step with that across resistor 27 proportionally to the increase in input voltage impressed on 19, but is smaller in magnitude than the voltage across resistor 27 by the amount of the voltage E_2 and the voltage drop through diode 40, the latter being small. In other words when the voltage drop across resistor 27 exceeds the voltage E_2 , then the voltage across resistor 42 plus the small drop in diode 40 plus the voltage E_2 is equal to the voltage drop across resistor 27. On the other 30 hand, if the drop across 27 is smaller than E_2 , there is no voltage across 42.

It will, therefore, be seen that the signal grids of the controlled signal transmission tubes do not have bias applied to them from the AVC circuit until the diode 40 becomes conductive, and 40 current begins to flow through resistor 42. In other words, the AVC action is delayed until the signal amplitude applied to the pentode section of tube 19 attains that value which will cause the cathode of diode 40 to become negative with respect to the anode thereof. The AVC bias applied to the controlled signal transmission tubes increases in magnitude as the received signal carrier amplitude increases. The AVC bias is impressed on the controlled stages after suitable filtration. The filter 50-51 denotes a filter network which is used in each of the grid connections, and the function of the filter network is to suppress audio frequency fluctuations of the 45 AVC bias. In practical use it might be desirable to insert a separate filter, similar to 50-51, so as to prevent feedback among the various tubes connected to one point on 42.

The condenser 43 should ordinarily be very 50 small, or zero, as its effect is to cause rectification of the audio component of the voltage impressed on diode 40, and the audio component may be quite large in comparison with the steady 55 component. If the condenser 43 is too large the AVC bias will increase when the received signal is strongly modulated, and decrease as the modulation decreases thereby reducing the fluctuation of the audio signal level. This last effect is not 60 customarily desired, because it amounts to a reduction of the volume range of the output. Preferably, a fraction of the total AVC voltage developed across 42 is applied to the last IF tube 13, since the gain of this tube must not be reduced to such a degree that the amplified signal impressed on the 2nd detector, which may be of

the order of 10 to 20 volts, is distorted. Tube 13 is therefore controlled by the voltage at a tap on resistor 42. The amount of control (if any) applied to the signal circuit of the converter 7 must also be limited to a relatively small amount, 65 by a similar connection, to avoid amplitude distortion of the IF output.

The diode 24-23 should be capable of generating a steady voltage of 50 to 100 volts across load resistor 27. The delay voltage E_2 can then be 10 15 to 30 volts, which leaves 35 to 70 volts for AVC action. If only two or three tubes are controlled in gain, the higher limit is satisfactory, but if five or six tubes are controlled or if some of the amplifiers are of the 6L7 or similar type with 15 control applied to two successive grids, the lower value of control voltage would be adequate for broadcast receivers. The delay in the AVC action is adjustable by virtue of the tap 30. Tap 30 should be so adjusted, in cooperation with tap 20 21, that diode 40 becomes conductive at an input signal level slightly below that which establishes the desired signal voltage at the second detector. Delay voltage can, alternatively, be increased to limit the noise produced between stations when tuning.

The condenser 28 may be quite large so as to take out a great deal of the audio component in the voltage impressed on diode 40, the limit to the size of condenser 28 being determined by 30 the magnitude of resistor 27 and by the permissible lag in the operation of the system. The larger the elements 28 and 27, the greater will be the time lag between a change in signal level applied to the pentode section of tube 19 and the 35 resulting change in AVC bias. The lag should be great enough so that the lowest frequencies which it is desired to reproduce in the signal output channel, including the second detector, will not cause fluctuation of the AVC bias, for this would 40 cause the output at these frequencies to be reduced. The permissible and necessary delay must be divided between network 28-27 and 50-51 in suitable proportions such that suitable lag is 45 produced while audio frequencies are prevented from reaching the signal grids of the controlled tubes.

While I have indicated and described a system for carrying my invention into effect, it will be apparent to one skilled in the art that my invention is by no means limited to the particular organization shown and described, but that many modifications may be made without departing from the scope of my invention, as set forth in 50 the appended claims.

What I claim is:

1. In combination with a signal transmission tube, a source of signal waves connected to the input electrodes of the tube, a signal utilization network coupled to the output electrodes of the 60 tube, a signal rectification network, responsive to waves impressed upon said transmission tube, for producing a direct current voltage varying in magnitude with the signal wave amplitude, a device of uni-directional conductivity, a source 65 of direct current voltage connected in circuit with said device and the first direct current voltage, the two direct current voltages being of opposite polarity and rendering said device non-conductive for signals of less than a predetermined amplitude, and an impedance in circuit with said device which is adapted to have a direct current voltage developed thereacross when said first direct current voltage exceeds the 70 magnitude of the second voltage and said device 75

becomes conductive, and means for impressing the third direct current voltage upon said transmission tube as a gain control voltage.

2. In a receiver of the type provided with a signal amplifier and a detector, an automatic volume control circuit of the delayed type, said control circuit including a diode rectifier network coupled to a point between said amplifier and detector for the impression of amplified signals on the rectifier network, a load resistor in the rectifier network adapted to develop a direct current voltage from the rectified signal current, a second diode, a source of fixed direct current voltage connected in series with said load resistor between the electrodes of the second diode, the two direct current voltages being in polarity opposition and rendering said second diode nonconductive for signals of less than a predetermined amplitude, a second load resistor disposed in the space current path of the second diode and adapted to develop a direct current voltage thereacross when said first direct current voltage exceeds said fixed voltage and renders said second diode conductive, and means for impressing the direct current voltage across said second load resistor between the input electrodes of said signal amplifier in a sense to reduce the amplifier gain as the received signal amplitude increases above a predetermined amplitude.

3. In a receiver of the type provided with a signal amplifier and a detector, an automatic volume control circuit of the delayed type, said control circuit including a diode rectifier network coupled to a point in the receiver for the impression of signals on the rectifier network, a load resistor in the rectifier network adapted to develop a direct current voltage from the rectified signal current, a second diode, a source of fixed direct current voltage connected in series with said load resistor between the electrodes of the second diode, the two direct current voltages being in polarity opposition and rendering said second diode nonconductive for signals of less than a predetermined amplitude, a second load resistor disposed in the space current path of the second diode and adapted to develop a direct current voltage thereacross when said first direct current voltage exceeds said fixed voltage and renders said second diode conductive, means for impressing the direct current voltage across said second load resistor between the input electrodes of said signal amplifier in a sense to reduce the amplifier gain as the received signal amplitude increases above a predetermined amplitude, and additional means for amplifying the signal energy prior to impression upon the first diode rectifier network.

4. In a receiver of the type provided with a signal amplifier and a detector, an automatic volume control circuit of the delayed type, said control circuit including a diode rectifier network coupled to a point between said amplifier and detector for the impression of amplified signals on the rectifier network, a load resistor in the rectifier network adapted to develop a direct current voltage from the rectified signal current, a second diode, a source of fixed direct current voltage connected in series with said load resistor between the electrodes of the second diode, the two direct current voltages being in polarity opposition and rendering said second diode nonconductive for signals of less than a predetermined amplitude, a second load resistor disposed in the space current path of the second diode and adapted to develop a direct current voltage

thereacross when said first direct current voltage exceeds said fixed voltage and renders said second diode conductive, means for impressing the direct current voltage across said second load resistor between the input electrodes of said signal amplifier in a sense to reduce the amplifier gain as the received signal amplitude increases above a predetermined amplitude, and means for adjusting the magnitude of said fixed direct current voltage thereby to delay the development of 10 said gain control voltage. 5

5. In a receiver of the type provided with a signal amplifier and a detector, an automatic volume control circuit of the delayed type, said control circuit including a diode rectifier network 15 coupled to a point in the receiver for the impression of signals on the rectifier network, a load resistor in the rectifier network adapted to develop a direct current voltage from the rectified signal current, a second diode, a source of 20 fixed direct current voltage connected in series with said load resistor between the electrodes of the second diode, the two direct current voltages being in polarity opposition and rendering said second diode nonconductive for signals of less 25 than a predetermined amplitude, a second load resistor disposed in the space current path of the second diode and adapted to develop a direct current voltage thereacross when said first direct current voltage exceeds said fixed voltage and 30 renders said second diode conductive, means for impressing the direct current voltage across said second load resistor between the input electrodes of said signal amplifier, and means in said gain control connection for filtering the pulsating 35 voltage components from the gain control voltage.

6. In a receiver of the type provided with a signal amplifier and a detector, an automatic volume control circuit of the delayed type, said control circuit including a diode rectifier network coupled to a point between said amplifier and detector for the impression of amplified signals on the rectifier network, a load resistor in the rectifier network adapted to develop a direct current voltage from the rectified signal current, a second diode, a source of fixed direct current voltage connected in series with said load resistor between the electrodes of the second diode, the two direct current voltages being in polarity opposition and rendering said second diode nonconductive for signals of less than a predetermined amplitude, a second load resistor disposed in the space current path of the second diode and adapted to develop a direct current voltage thereacross when said first direct current voltage exceeds said fixed voltage and renders said second diode conductive, means for impressing the direct current voltage across said second load resistor between the input electrodes of said signal amplifier in a sense to reduce the amplifier gain as the received signal amplitude increases above a predetermined amplitude, and means for adjusting the signal input to the control circuit in relation to the input to said detector.

7. In combination with a signal transmission tube, a source of signal waves connected to the input electrodes of the tube, a signal utilization network coupled to the output electrodes of the tube, a signal rectification network, responsive to waves impressed upon said transmission tube, for producing a direct current voltage varying in magnitude with the signal wave amplitude, a device of uni-directional conductivity, a source of direct current voltage con- 75

5 nected in circuit with said device and the first direct current voltage, the two direct current voltages being of opposite polarity and rendering said device non-conductive for signals of less than a predetermined amplitude, and an impedance in circuit with said device which is adapted to have a direct current voltage developed thereacross when said first direct current voltage exceeds the magnitude of the second voltage and

said device becomes conductive, means for impressing the third direct current voltage upon said transmission tube as a gain control voltage, said rectification network including an impedance across which said first direct current voltage is developed, and said device comprising a diode having its cathode connected to a point on said last impedance. 5
